UNITED STATES PATENT OFFICE.

JOHN E. NORWOOD, OF BALTIMORE, MARYLAND.

PISTON RING.

1,404,540.

Specification of Letters Patent. Patented Jan. 24, 1922.

Application filed September 8, 1918. Serial No. 252,887

To all whom it may concern:

Be it known that I, JOHN E. NORWOOD, a citizen of the United States, residing at Baltimore, in the county of Baltimore, State 5 of Maryland, have invented certain new and useful Improvements in Piston Rings; and I do hereby declare the following to be a full, clear, and exact description of the invention, such as will enable others skilled 10 in the art to which it appertains to make and use the same.

This invention relates to piston rings and more particularly of that class wherein the ring is provided with a circumscribing oil 15 receiving channel in its outer periphery, which in operation, holds the oil in position to seal the ring.

In a ring of this character as ordinarily constructed, and in which the ring contacts 20 with the cylinder at both sides of the oil groove, the contacting surface of the ring at both sides of the groove is of material transverse extent so that the oil on the face of the cylinder does not readily flow to a 25 groove.

It is the object of the present invention to provide a construction wherein the contacting surface of the ring at one side of the groove will have a minimum transverse 30 extent so that said contacting surface while holding the oil against too ready flow from the groove will yet permit of the flow of oil into the groove more readily because of the cylinder pressure against the oil.

35 A further object of the invention is to provide an improved construction wherein such oil as may pile up in front of the ring will be directed to the groove of the ring instead of passing to the ring receiving 40 channel of the piston.

In the drawings:

Figure 1 is a section taken longitudinally through a portion of the cylinder and piston of an explosive engine equipped with a 45 ring embodying the present invention.

Figure 2 is a sectional perspective view of the ring shown in Figure 1.

Figure 3 is a view similar to Figure 1, showing a lesser portion of the cylinder and 50 piston and illustrating a modification of the ring.

Figure 4 is a view similar to Figure 3 showing a further modification.

Referring to the drawings there is shown 55 a portion of the cylinder 5 of an explosive engine in which is disposed a piston 6 hav-

ing the usual circumscribing channel 7 to receive a packing ring.

The packing ring embodying the present invention consists of a short hollow cylinder 60 8 of the usual resilient material and with the usual opening to permit of compression and expansion of the ring radially.

The end walls 9 and 10 of the ring are flat and at right angles to the inner periphery 11 and these end walls 9 and 10 closely but slidably fit against the corresponding side walls 12 and 13 of the ring receiving channel 7 of the piston.

In the outer periphery of the ring 8 is 70 formed a circumscribing groove which in the embodiment illustrated has one wall 14 at right angles to the outer periphery 15 of the ring while the other wall 16 extends from the bottom of the wall 14 and at an 75 acute angle thereto and terminates at the outer periphery of the ring. From the outer periphery 15 of the ring at the line of intersection thereof by the groove wall 16 there extends a bevel 17 to the end face 80 12 of the ring. This bevel is straight and at an acute angle to the inner surface of the wall of the cylinder 5. The inner end of this bevel terminates substantially at the periphery of the piston. 85

This ring in practice is disposed in the piston adjacent the end that receives the explosion pressure and the ring is disposed with its end bevel 17 in the direction of the explosion chamber of the cylinder. 90

In practice, as the piston moves against compression the film of oil on the contacting face of the cylinder is not scraped off by the portion of the contacting surfaces of the ring lying between the bevel 17 and the 95 groove wall 16. This is first by reason of the fact that the film of oil is very thin and clings to the cylinder wall by capillary action and with sufficient tenacity to overcome the comparatively slight inclination to 100 scrape that is had by this very narrow surface. Again, as soon as any scraping begins there is a piling up of the oil in the angle between the bevel 17 and the wall of the cylinder and against this small ridge of oil 105 there impinges the cylinder pressure which increases under the compression and serves to force past this narrow face and into the groove of the piston the excess of oil thus piled up, that was distributed onto the face 110 of the cylinder during the just previous intake stroke of the piston.

It will be noted that the portion 17 of the ring is disposed at an angle to the face 15 of the ring and is located at the other side of the groove from the face 15. The extensive contacting surfaces of the ring between the groove and the end 10 of the ring however prevents so free a movement of the ring over the oil which therefore is collected in the groove of the ring to form an oil seal.

- 10 Again by reason of the bevel 17 the scraping of oil from the surfaces of the cylinder does not occur until the end face 12 of the piston ring is beyond the line of scraping and thus, the scraped oil instead of being 15 deflected at right angles into the slight interspace between the end wall 9 of the ring and the corresponding wall 12 of the channel 7 initially piles up within the angle and its return flow is across this interspace.
- 20 Referring to Figure 3 of the drawings, there is shown a modification wherein, instead of forming the bevel 17, the ring 8' has an oil retaining groove bounded by the radial wall 14' and the second wall 16' at 25 an acute angle thereto. A second oil receiving groove is formed which is bounded by a radial wall 20 that touches the periphery 15' of the ring at substantially the same line with the wall 16' to form the same minimum 30 contacting surface as in the first instance that will let the oil into the groove between the walls 14' and 16' under pressure of the expansion and will retard its outflow. From the base of the wall 20 of the second groove 35 there extends at an acute angle thereto the wall 21 that meets the end faces 9' of the ring inwardly of the outer periphery 15' of the ring. Thus, the oil may freely enter this second groove. In this construction the 40 first named groove holds the oil as a seal while the second groove will arrest the oil that would otherwise be deflected into the interspace between the end 9' of the ring and contacting wall of the ring receiving 45 channel of the piston.

In Figure 4 of the drawings there is shown a further modification wherein the groove and bevel as shown in Figure 1 is embodied in a two-piece ring. This two-piece ring includes the annular members A and B. The member B has a cylindrical outer periphery 15" that contacts with the wall of the cylinder 5". One end face 10" of the member B contacts with the wall 13" of the ring receiving channel 7" of the piston. The other end face 14" of the member B, adjacent the peripheral face 15" is at right angles to the axis of the ring and corresponds to the groove wall 14 of Figure 1.

50 A rabbet C is formed in the intersection of the face 14" with the inner periphery of the member B in this rabbet is fitted the corresponding portion D of the ring member A, which portion D is of correspondingly 55 reduced external diameter. From the base

of the wall 14' the member A extends at an acute angle to said wall 14" as shown at 16", to touch the face of the cylinder wall 5". Thence the member A is beveled at 17" to the end face 9" of the member A that contacts with the wall 12" of the ring receiving channel.

In the use of this two-part ring, the member A is disposed in the direction of compression and oil passes by capillary action 75 and by pressure, across the line of intersection of the faces 16" and 17" to the oil pocket or groove between the faces 16" and 14". The oil packs into this groove. Now the oil will of course flow into this groove 80 past this narrow edge readily but will not pass readily between the face 15" and the wall of the cylinder. The consequence is that the subsequent pressure past this narrow edge against the wall will be distributed 85 over the faces 16" and 14" and in accordance with the well known hydraulic principles, will exert a strong pressure to slide the ring members with respect to each other and cause the member A to bear tightly 90 against the wall 12" and the face 10" to bear tightly against the wall 13". Thus is the composite ring caused to completely fill 95 the channel from side to side and prevent leakage.

What is claimed is:

1. A piston ring for internal combustion engines the same comprising a pair of annular members, the respective annular members each having a flat axial end face, the flat faces of the respective members being adapted to bear against opposite walls of the piston groove, the said members being also in contact with each other throughout their length along annular surfaces, said annular surfaces being in the form of an annular step so that each member has a contacting surface in cylindrical form and one which is plane and at right angles to the axis, one said ring member also having a cylindrical 110 surface which contacts the cylinder wall, the other having a peripheral edge which likewise contacts the cylinder wall, the edge being formed by the intersection of surfaces placed at acute angles to the axis, the cylindrical surface of the other ring member being provided by surfaces at right angles to the axis so that there is formed between the members a peripheral groove with a straight 115 side and an inclined side.

2. A spring piston ring for internal combustion engines the same having a peripheral groove, a flat cylinder contacting surface on one side of the groove, a cylinder engaging peripheral edge on the other side of the 125 groove, the groove having a wall at right angles to the axis and a wall which is inclined to the axis, the latter terminating in the said peripheral edge, the end surface of the ring adjacent the edge being beveled at 130

an acute angle to the axis forming an inclined surface leading from the axial end surface of the ring to the said edge.

3. A spring piston ring for internal combustion engines the same having a continuous annular peripheral groove, a scraping edge on one side of the groove, a flat contacting surface on the other side of the groove, an axial end surface adjacent the edge being

beveled, i. e. having a peripheral portion formed at an acute angle to the axis.

In testimony whereof, I affix my signature in the presence of two witnesses.

JOHN E. NORWOOD.
